CLOTH CUTTING MACHINE

Emanuel Rodriguez Morando, New York, N. Y.

Application November 19, 1941, Serial No. 419,663

6 Claims. (Cl. 30—275)

This invention relates to a fabric or cloth cutting machine, particularly of a convertible or swivel type.

One of the main objects of this invention, is the left hand outwardly extending bracket member that supports the motor and knife operating mechanism, in which inner V's or other cutting operations in the inner portions of goods and patterns may be cut. The cloth or pattern to be cut is straddled by the bracket having an overhanging arm, to any extent that may be desired, usually about six to eight inches, for straight or diamond cut V's in coats of men's wearing apparel.

Another important object of this invention, is the convertible and swiveled type of a cloth cutting device, in which the bracket member having an outwardly vertical handle portion, is adaptable of being turned from the side position of the cutting knife, to the rear position, so the device may also be used in cutting from the outside of the goods or patterns.

Another important feature of this invention, is the reinforcement means for the knife blade, by a downwardly extending guide member from the upper end portion of the bracket arm onto which is supported the motor, and has a suitable space between its free end and the table plate onto which the lower base portion of the bracket is supported in its convertible connection. In present machines the motor is supported on a similar member, but in this invention it does not provide any support, but merely provides reinforcement means for the straight flat blade during its cutting operations.

Other objects of this invention will appear as the description proceeds in the following specification, accompanied by the annexed drawing, in which—

Figure 1 is a reduced plan view taken on line 1—1 of Figure 2, showing the bracket operating a parallel relation to the inner cutting knife and V of the coat pattern.

Figure 2 is a front elevational view of the cloth cutting machine shown operating in Figure 1.

Figure 3 is a side view in elevation of the same machine shown in Figure 2.

Figure 4 is a fragmentary view of that portion showing the cutting knife in Figure 3 provided with an outer reinforcement.

Referring to the drawing, there is shown a motor cloth cutting machine 10, having the usual electric motor A that is supported onto an extending bracket member B as at C to the upper arm portion B2, while the lower base portion B3 is secured to the table plate 12 as at D, by means

of a swivel connection or recessed portion D', locking means, for example by stub pins D'', and a screw D'''. A reciprocating knife blade E having double cutting edges F and a sharp pointed end H is positioned as shown, so that it may be specially adapted for cutting inner V's in the coat patterns P. A foot-guide rod 14 and plate holder 15 for the cloth is shown in front of the knife as is the present method now used. If so desired to reinforce the knife, a guide member EE as shown in Figure 4 may or may not be used.

Also the bracket B may be of a swivel type, that is it may be swung around so the knife may be adaptable for cutting through any patterns P from the outside, in which the bracket may follow the knife in alignment. The upper arm portion B2 and lower base portion B3 of the bracket B are connected by the vertical handle portion B4, and all of which must be firmly secured for example, by a recessed portion D', dowel pins D'' and screw D''', in which the screw D''' is loosened, so the base portion b may be turned around and over the pins D'', and then set into the pins again and locked by the screw D'''.

The knife E is of the straight type, and may be provided with an intermediate guiding and supporting means, as by the extending member EE, which is of sufficient length so as to surround the blade portion of the knife E, that is the flat sides thereof. The member EE may have, if so desired, an inner slotted portion for the sliding fit of the side portions of the blade E. The cloth plate 15 may be used for reinforcing the knife blade, if the guide member is not used, but it is preferred that the guide member provides the necessary reinforcement means therewith.

The table plate 12 is provided with ball casters BC, so the device may be maneuvered from any angle in any desired position, such as for sliding sideways under the cloth garments P to be cut. The plate 12 has a slot 12a for the V pointed end H of the knife blade E to operate therein when in the lowermost position. Present cloth cutting machines will not allow the sideway movement, due to the elongated rollers, hence is the necessary use of these ball casters BC to allow free maneuvering of the machine in any desired direction.

It is to be understood that the foregoing description and the drawing, are merely illustrative of my invention, and I reserve the right to make any alterations and amendment to improve further my invention, providing same comes within the scope of the appended claims.

What I claim as new and desire to secure by Letters Patent of the United States, is as follows:

1. In a cloth cutting device of the character described, including a table plate, said table plate provided with ball casters, a bracket having an upper arm and lower base portion with an outwardly vertical handle portion therebetween, said base portion swivelly mounted onto said table plate, an electric motor mounted onto said upper arm portion, said motor connecting to any suitable current supply, a straight blade cutting knife operated by said motor and extending downwardly therefrom, a guide member providing reinforcement means for said knife blade, having its free end suitably spaced above said table plate, said device adapted for cutting inner portions of goods and patterns and further adaptable for cutting into the patterns from the outside thereof, by means of the swivel connection of the base portion of said bracket and said table plate.

2. In a cloth cutting device of the character described, the combination of a table plate provided with ball casters, a bracket having an upper arm and base portion with a vertical handle portion therebetween, a motor mounted onto the end of said upper arm, said base portion mounted onto said table plate, said base portion adapted to be unsecured from said table plate, whereby said bracket may be turned at about 90 degrees, more or less, thereby providing a cutting machine of the straight knife blade type to be operated for cutting inner portions of goods or for cutting from the outside of said goods.

3. In a cloth cutting device of the character described, including a table plate provided with ball casters, a motor supporting bracket mounted onto said table plate, said bracket having an outwardly vertical handle portion from which an upper arm portion extends in about a parallel relation to said table plate and base portion of said bracket, the end of said upper arm portion having the motor secured thereto above said table plate, said motor connecting to a suitable current supply, said motor having a reciprocating straight blade knife therewith, said knife blade slideable in a guide member extending downwardly from said motor, a cloth plate adjustable therewith, said guide member terminating into a free end portion directly above said table plate, guiding means for said knife blade provided therewith, said bracket adapted to be convertible in different positions to allow said knife blade to cut at the inner portions of patterns whereby said vertical handle portion is held by the hand and the usual handle on said motor is used for steering the device during its cutting operation by the other hand, and to allow for the cutting of patterns from the outside of the patterns.

4. In a cloth cutting machine of the character described, including a table plate, a bracket mounted thereon, said bracket having a base portion and an upper arm portion with a vertical handle portion therebetween, said base portion provided with means to swivel said bracket into different positions, an electric motor secured onto the end of said upper arm portion, a reciprocating knife blade operable therewith directly above said table plate, said knife blade provided with a reinforcing and guiding member extending downwardly from said motor and end arm portion, said motor connected to any suitable current

supply, said handle portion of said bracket adapted to be held by one hand while the other hand uses the regular steering handle of the machine behind the knife and motor and above the end of the upper arm portion of said bracket, whereby said machine is adapted to operate said knife blade for cutting inner V's and the like at the inner portion of cut patterns, and further adapted by turning the handle from its side portion to said cutting knife blade, to the rearwardly position behind the knife blade when cutting from the outside of said patterns and through the cloth or goods from which the patterns are being cut.

5. In a cloth cutting machine of the character described, including a table plate, a bracket having a base portion and an upper arm portion with a vertical handle portion therebetween, said base portion mounted onto said table plate, said table plate having ball casters, a motor supported onto the end of said upper arm portion, said vertical handle portion being in an extended outwardly position from said table plate and said motor, said table plate provided with swiveling means to instantly convert said handle portion in a different position, a reciprocating knife blade operable downwardly from said motor, said motor being connected to any suitable supply of power, said knife blade reinforced by a guide member extending downwardly from said motor support, said guide member terminating into a free end above said table plate, said handle portion of said bracket being on the outside of the goods to be cut on the inner portion thereof by said knife blade, and when said knife blade is used for cutting patterns from the goods the handle is turned to its convertible position in the rear of said knife blade so the handle portion may follow through the cut portions of said goods and patterns therewith.

6. In a cloth cutting machine of the character described, including a table plate provided with ball casters, a bracket mounted thereon, said table plate having a recessed portion, said bracket having a base portion and an upper arm portion with a vertical handle portion connecting therebetween, said recessed portion of said table plate provided with locking means, such as by spaced dowel pins onto which the base portion of said bracket may be secured in a suitable swiveled position, said base portion and table plate firmly secured, such as by a screw locking member, an electric motor mounted onto the end of said upper arm of said bracket directly above said table plate, a reciprocating knife blade operable downwardly towards said table plate by said motor, said knife blade provided with a reinforcing and guiding member extending also downwardly from said motor and arm end portion, a cloth plate adjustable therewith, said vertical handle portion held by one hand on the outside of goods to be cut at the inner portions thereof, while the other hand may be applied to the usual motor handle to assist in the steering and cutting operation by said knife blade and motor, said vertical handle when convertible to the rear of said knife blade by said swivel means of said bracket and table plate allows said knife blade to cut patterns from the goods in which said vertical handle follows through the cut portion behind the cutting knife blade.
